UNITED STATES PATENT OFFICE.

PERRY W. BARKER, OF YOUNGSTOWN, OHIO.

AUTOMATIC FEEDER FOR PRESSES.

1,422,914.

Specification of Letters Patent. Patented July 18, 1922.

Application filed September 22, 1921. Serial No. 502,415.

To all whom it may concern:

Be it known that I, PERRY W. BARKER, a citizen of the United States, residing at Youngstown, in the county of Mahoning and State of Ohio, have invented certain new and useful Improvements in Automatic Feeders for Presses, of which the following is a specification.

It is usual in job printing work to place a slip sheet of blank paper between successive printed sheets as they are taken from the press and laid one upon the other, in order that the printed sheets may not be soiled by the fresh ink on adjacent sheets.

The purpose of my invention is to provide simple and efficient means for performing this operation automatically.

For the purposes of illustration, I have shown my device attached to a Miller automatic feeder and in connection with a Chandler & Price press, although it is not limited to such use.

I provide a support for the slip sheets attached to the elevator of the automatic feeder, and a pneumatic transfer mechanism which takes a slip sheet from the top of the stack and places it upon the top of the last printed sheet that has been removed from the press by the automatic feeder.

The pneumatic mechanism is so arranged that suction is applied alternately to the slip sheets and the sheets fed from the supply of the automatic feeder.

In the accompanying drawings, which illustrate the preferred form of my device,

Figure 1 is a side elevation showing the device attached to the automatic feeder;

Figure 2 is a front view of the same parts;

Figure 3 is a top plan view of the slip sheet table and feeding device;

Figure 4 is a perspective view of the pick up suction head for the slip sheets and supporting means therefor;

Figure 5 is a section of the suction head shown in Figure 4;

Figure 6 is an enlarged detail view, partly in section, of parts of the pneumatic connections and valves; and

Figure 7 is a side elevation of the slip sheet table and its support.

As my invention relates to an attachment,

it has not been considered necessary to illustrate the press and automatic feeder in detail.

There is shown a part of the power wheel 1

and the platen 2 of the press. The automatic feeder comprises broadly an elevator 3, a table 4 upon which the printed sheets are deposited by pick up fingers 5 carried by a rod 6 extending laterally from an arm 7 carried by an oscillating shaft 8 which is operated in the usual manner, and certain pneumatic connections hereinafter referred to. These parts are all old.

Attached to the elevator 3 by set screws 10 are clamps 9 from which rise standards 11 that support at their upper ends a table 12. This table is provided with side gages 13 and a rear end gage 14, all of which are made adjustable as illustrated and are held in desired positions by set screws 15 and 16 respectively. Upon this table are placed the slip sheets, the guides being adjusted to correspond with the size of the sheets and also so as to bring the leading edges of the sheets in line with the edge of the table 12.

As further means of support for this table hooks 17 are provided which hook over the upper edge of the elevator and are connected by springs 18 to eyes 19 in the clamps 9.

Carried by the rod 6 is a split clamp 20 held in adjusted position by a set screw 21. An arm 22 is provided with a slot through which passes a set screw 23 threaded into the clamp 20. This arm 22 carries the suction head 24 which picks up the slip sheets 25. To the suction head is connected a pneumatic 26. These adjustments permit the suction head to be placed in proper relation to the slip sheets. Furthermore the front edge of the pile of slip sheets may be adjusted vertically by means of a thumb screw 27.

Pipe 28 leads from the main air system beneath the elevator, and is connected with the automatic feeder through a pipe 29 controlled through a valve 30. Connected to pipe 28 is a pneumatic connection 31 which leads to a fitting 33 supported from the feeding device and which contains valves 32 and 34. To this fitting is connected the pneumatic 26 above described that is held to the rod 6 by clips 35.

Also supported by said fitting and leading to the main pump located beneath the printing press and not shown, is a blower pipe 36 that is carried to a point adjacent the front edge of the pile of sheets near their center.

Connected to the rock arm 7 is a strap or other member 37 that is connected by a

chain 38 and adjusting device 39 to a member 40 attached to operate valve 34. This member 40 carries a weight 41.

- The operation of the device is as follows:
- 5 Assuming that the press and the automatic feeder have been properly set for the work to be performed, the pile of slip sheets is adjusted by means of thumb screw 27 until the top of the pile is in proper relation to the
  - 10 suction head 24. Preferably there should be a space of about one-eighth of an inch therebetween. At this time valves 30 and 32 should be closed.

Valve 30 is then opened, permitting the automatic feeder to operate. When the first printed sheet is being delivered to the table 4 by the pick up fingers 5, valve 32 is opened. This permits the suction head 24 to pick up the top slip sheet. As the pick up fingers 5 move down to grasp the next printed sheet, the suction head 24 will carry the slip sheet over the printed sheet that has been deposited on the table 4. At the limit of this movement, the arm 7 through connecting members 37, 38 and 40 has closed the valve 34 thereby permitting the sheet to drop upon the printed sheet, and also permitting the suction in the pneumatic system to be employed in operating the automatic feeder.

As the rocker arm and pick up fingers move up, the weight 41 operates to open the valve 34 and cause the suction head 24 to pick up the next slip sheet.

35 This operation continues until either the slip sheets or the sheets in the elevator of the automatic feeder have been exhausted. The exhaustion of either pile of sheets causes both mechanisms to stop.

40 The upper end of the blower 36 is placed adjacent the edge of the sheets so as to cause them to vibrate slowly and thus render it easier for the top sheet to be picked up by the suction head 24. The slant of the table 45 12 also assists this action.

If it is desired to operate the press and automatic feeder without the slip sheet feeding device, it is only necessary to close the valve 32. It is obvious that the whole attachment can be quickly and readily removed from the machine.

This device may also be used for assembling duplicate sheets with previously printed sheets, by placing the original sheets 55 on table 12 as if they were slip sheets.

Although I have illustrated the device for convenience' sake in connection with a particular form of printing press and automatic feeder, it is obvious that my invention is not limited thereto, and that it can be applied to other machines without departing from the spirit of the invention or the scope of the appended claims.

I claim as my invention:

- 65 1. In a slip sheet feeding device for print-

ing presses, the combination of an oscillating member, pick up devices carried by said member for transferring the printed sheets to a table, a pick up device for the slip sheets mounted for rotary and longitudinal 76 adjustment on said member for transferring the slip sheets to said table, and means for automatically rendering the two pick up devices alternately operative.

2. In a slip sheet feeding device for printing presses, the combination of an oscillating member, pick up devices carried by said member for transferring the printed sheets to a table, a pick up suction head also carried by said member for transferring the 80 slip sheets to said table, and means for automatically rendering the two pick up devices alternately operative.

3. In a slip sheet feeding device for printing presses, the combination of an oscillating member, pick up devices carried by said member for transferring the printed sheets to a table, a pick up suction head also carried by said member for transferring the slip sheets to said table, pneumatic connections 90 to said suction head, a valve therein, and means for automatically closing and opening said valve during the oscillation of said member, whereby the two pick up devices are operated in alternation.

4. In a slip sheet feeding device for printing presses, the combination of an oscillating member, pick up devices carried by said member for transferring the printed sheets to a table, a pick up suction head also carried by said member for transferring the slip sheets to said table, pneumatic connections 100 to said suction head, a valve therein, and means for closing said valve during the movement of said oscillating member in one direction and separate means for opening said valve during the movement of said oscillating member in the other direction, whereby the two pick up devices are operated in alternation.

5. In a slip sheet feeding device for printing presses, the combination of an oscillating member, a clamp mounted on said member for rotary and longitudinal adjustment thereon, an arm adjustably mounted on the 115 clamp, a pick up suction head for slip sheets carried by said arm, and means for rendering the suction head operative during movement of the oscillating member in one direction and inoperative during movement in the other direction.

6. In a slip sheet feeding device for printing presses, the combination of an oscillating member, a pick up device for the slip sheets mounted for rotary and longitudinal 125 adjustment on said member, and automatic means for rendering the pick up devices operative to transfer a slip sheet to a table during movement of the member in one direction.

7. In a slip sheet feeding device for printing presses, the combination of an oscillating member, a pick up suction head carried by said member for transferring the slip
5 sheets to a table, pneumatic connections to said suction head, a valve therein, means operated by said member for closing said valve

during the oscillating movement of the member in one direction, and separate means for opening said valve during movement of the member in the other direction.

In testimony whereof, I have hereunto
subscribed my name.

PERRY W. BARKER.
